W. E. WILLIAMS.

METAL SHEATHING FOR CARS AND HOUSES.

APPLICATION FILED NOV. 26, 1913.

1,240,635.

Patented Sept. 18, 1917.

UNITED STATES PATENT OFFICE.

WILLIAM ERASTUS WILLIAMS, OF CHICAGO, ILLINOIS.

METAL SHEATHING FOR CARS AND HOUSES.

1,240,635.

Specification of Letters Patent. Patented Sept. 18, 1917.

Application filed November 26, 1913. Serial No. 803,133.

To all whom it may concern:

Be it known that I, WILLIAM ERASTUS WILLIAMS, a citizen of the United States, and a resident of Chicago, county of Cook, 5 State of Illinois, have invented a new and useful Improvement in Metal Sheathings for Cars and Houses, of which the following is a specification.

My invention relates to sheathing that 10 combines a panel effect with a smooth exterior, provides air spaces and gives a stiff ribbed construction to resist distortion.

The object of my invention is to provide 15 an inexpensive, light sheathing that will contribute materially to the strength of the structural framework of the car or house.

My sheathing is made in panels complete 20 in themselves which are applied to the side of the structure in units of the desired size, and were it practicable to handle the sheathing in lengths equaling the length of the structure to be covered, my sheathing could be so constructed.

Other sheathings resembling mine in appearance 25 are usually made with distinct, separately affixed slats which add little or no strength, and when they have a more or less continuous base member the latter is not usually of such form as to give a plate girder effect in the structure.

My sheathing is applied to the car with very much less labor, is lighter and furnishes a "plate girder" to the side of the car.

Reference will be had to the accompanying drawings in which Figure 1 is an edge view of the sheathing assembled on the side of a car, house, or any structure that it may be used upon.

Fig. 2 is an elevation of the back or inside 40 of the sheathing.

Fig. 3 is a perspective view of the sheathing from the outside.

Fig. 4 is a section of the sheathing on line 4-4 of Fig. 2.

Fig. 5 is a section of the sheathing through line 5-5 of Fig. 2, showing the screw, bolt, or rivet hole.

Fig. 6 is a section of the sheathing on line 6-6 of Fig. 2.

Fig. 7 is a section on line 7-7 of Fig. 2. Fig. 8 shows the end of one of the slats

that cover the joint between the sections of the sheathing.

Fig. 9 shows the end of a modified form.

Fig. 10 shows a section of the structure of 55 Fig. 9.

Fig. 11 shows the rear face of the form shown in Figs. 9 and 10.

In the drawings 1 indicates a side girder or the side of the car, house or structure, to 60 which the sheathing is secured.

The sheathing involves spaced inner and outer plates and the inner plate is usually made up of a series of abutting plate sections 2 in the same plane, each provided 65 with low outwardly projecting preferably embossed ribs 8. The outer plate usually consists of primarily independent similar abutting plate sections 3 each of which is provided on its inner face with equally 70 spaced, equally projecting parallel and vertical ribs 4 formed by bending or folding the sheet in such manner that its general outer face, when completed, is plane and nearly continuous although slightly grooved 75 along the lines of the ribs. The marginal portion of each plate section is bent inwardly to the inner plate at a distance from the nearest rib equal to the distance between adjacent ribs, to form an overhanging offset, 80 and is then carried onward to some distance along the face of the inner plate. The outer and inner plates are assembled in such position that on one side the marginal portion 9 of the inner plate projects to some distance beyond the marginal portion 6 of the outer plate section (Fig. 4) while at the opposite side of the superposed sections the marginal portion 5 of the outer plate projects beyond the margin 10 of the inner 85 plate (Fig. 6), so that when the sections are assembled as in Fig. 1, the plates overlap, breaking joints. The widths of the marginal portions are such that when they abut as shown in Fig. 1, the distance between 90 adjacent overhanging offsets is substantially equal to the distance between consecutive ribs 4, whereby there is formed a dovetail channel, having reentrant angles 7, to receive a "slat" 18 marginally bent to fit the 100 channel and having its outer face in the plane of the outer faces of the plate sections

3, so that the slat in place is practically indistinguishable from the inter-rib portions of the plate section. At suitable points along the rib lines, the outer plate is pressed 5 inward to form small cups extending to the inner plate and perforated at the bottom to receive screws, bolts or rivets 15 which pass through registering holes 14 in the plate 2 and bind the plates together. The sheets 10 when in proper relation are further joined by marginal spot welds at 11 and also by welds at 12 where the ribs 4 cross the ribs 8 of the rear or inner plate, whereby the sheets are integrally connected to form a 15 rigid cellular structure. The cellular sections are secured together and to the car or other structure by screws or the like passing through holes 16 in the marginal portions 5, 6, 9, 10 of the plate sections and after the 20 cellular sections are thus joined the slats 18 are forced from below into their channels covering the fastening 17 and are themselves secured in place by screws or rivets at 19.

In Figs. 9, 10, 11, I show wires 20 extending 25 across the back of the plate 3 in place of plate 2. The wires 20 are welded down flush, at the points 21, into the ribs, and the ends of the wires are bent over at 22 and welded to the plate 3 on the inside of the 30 acute angle 7, thus completely tying across the summits of the ribs at the back of plate 3.

The wires 20 may be spaced sufficiently close together to give all the strength required 35 across the back of plate 3.

The spaces on the back of plate 3, see Fig. 9, may be filled in with cement 23 when desired.

In place of wires 20 I may use strips of 40 metal provided with ribs or indentures 8 and weld them to the back of plate 3 for the stiffening backing.

With my sheathing the plate 2 forms the web member of a regular plate girder when 45 fastened to the car or structure side and gives a strength not obtained with the other panel styles of sheathing in use. The plate 3 welded up as described, also assists in forming the girder effect.

50 I can weld the plate 2 to the summits of the ribs or flanges 4 of plate 3 without the indentures 8, but I prefer to use them for giving added stiffness to the plate 2.

The plates 2 and 3 may be secured together 55 in any suitable manner by bolts, rivets, brazing or welding, but I prefer to use the latter as it makes the plates as one plate as to rigidity.

My construction provides air spaces in the 60 body of the sheathing and on account of the ribs, which separate the air spaces, thin sheets of metal may be used for the plates.

The front and rear plates, connected as 65 they are to each other at the sides or edges of the panels where the sections join each

other, assist materially in a plate girder result for the side of the structure to which the sheathing is attached.

What I claim is:

1. In a structure of the class described, 70 the combination with an outer plate made up of sheets each bent to form on one face parallel ribs and on the other face corresponding panels, the successive sheets overhanging marginally to form dovetail grooves 75 to receive joint panel slats, joint slats fitting said grooves, respectively, transverse backing members integrally secured to the inner margins of all the ribs of the sheets, respectively, means for securing each united 80 front and backing member to the wall to be sheathed, and means for securing each joint panel in its groove.

2. A sheathing composed of a front plate 85 provided with stiffening ribs made therein in a manner to give the appearance on the outside of a slatted sheathing said plate formed at its edges parallel to the ribs to provide a locking groove for a joint slat, a joint slat adapted to fit the groove and bridge the space between the sections of the sheathing; with a backing plate fixed to the front plate across the summits of the ribs.

3. A sheathing composed of a front plate 95 provided with stiffening ribs formed therein in a manner to give the appearance on the outside of a slatted sheathing, said plate bent at its edges parallel with the ribs in a manner to provide a locking groove for a joint slat; with a backing plate fixed to 100 the front plate across the summits of the ribs and the plates overlapping each other at the edges in a manner to cover up the joint seams between the sections and with a joint slat adapted to fit the grooves and 105 bridge over the space of the joint between the sections.

4. A sheathing composed of a front plate having ribs made therein whereby panel or slatted effect is produced on the outside surface and the edges of said plate bent in a manner to produce a locking groove for an adjacent section of the sheathing or a cover slat and terminating in a surface adapted to be fixed to the side of the structure; with 110 a backing plate secured to the inside of the said front plate.

5. A sheathing composed of a front plate having ribs made therein whereby panel or slatted effect is produced on the outside surface and the edges of said plate bent in a manner to produce a locking groove for an adjacent section of the sheathing or a cover slat and terminating in a surface adapted to be fixed to the side of the structure; with 115 a backing plate secured to the inside of the said front plate and a cover slat adapted to interlock in the grooved ends of the sections of the sheathing.

6. The combination with a metal facing 130

sheet having its exterior surface divided into panels by folds forming on the opposite side of the sheet ribs of uniform width and pressed inward at intervals to form rigid 5 integral cup - like struts extending to the plane of the inner margins of said ribs, of a transverse member integrally connecting said margins.

In witness whereof I have hereunto sub-

scribed my name on this 22nd day of November, 1913, in the city of Chicago in the county of Cook and State of Illinois in the presence of two subscribing witnesses.

WILLIAM ERASTUS WILLIAMS.
